CANDLE HOLDER OR THE LIKE

John O. Van Koert, Newburyport, Mass., assignor to Towle Manufacturing Company, Newburyport, Mass.,
a corporation of Massachusetts

Application May 12, 1953, Serial No. 24,984

Term of patent 14 years

(Cl. D48—2)

FIG. 1.

FIG. 3.

FIG. 2.

FIG. 4.

Fig. 1 is an orthographic projection of one side of the top of the candle holder, embodying my new design;

Fig. 2 is an orthographic projection of the front of my new design, the back side being of corresponding shape;

Fig. 3 is an orthographic projection of my new design, the other side being of corresponding shape; and

Fig. 4 is a vertical diametrical section taken on the line 4—4 of Fig. 1 showing the contour of the top surface.

I claim:

The ornamental design for a candle holder or the like, substantially as shown.
